DRILL CENTRALIZERS

Birger Zettergren, Nacka, Sweden, assignor to Atlas Copco Aktiebolag, Nacka, Sweden, a corporation of Sweden

Filed Mar. 18, 1963, Ser. No. 265,829

Claims priority, application Sweden, Mar. 29, 1962, 3,512
9 Claims. (Cl. 308—3.9)

This invention relates to drill centralizers and particularly to drill centralizers of the type having a pair of guiding arms swingable about pivots on a base between active and inactive positions. In drill centralizers of this type it sometimes can happen that the guiding arms during operation unintentionally leave inactive position and cause damages by contacting movable parts. By that reason the guiding arms have often been arranged lockable in inactive position. Hitherto known lockable drill centralizers, however, are usually found to be comparatively complicated and do not provide easy synchronization and simultaneous movement of the guiding arms to their different positions as would be desirable.

It is a main object of the invention to provide a drill centralizer of the above type in which the guiding arms are retained in active as well as inactive positions by means of a sole simple spring means. A further important object is to provide a drill centralizer of the above type in which the movement of the guiding arms is effectively synchronized making it possible to move both guiding arms simultaneously to active or inactive positions by a single movement of one's hand.

The invention will be described more in detail by the aid of the enclosed drawing. Therein FIG. 1 shows a drill centralizer according to the invention seen from above. FIG. 2 shows a side view of the drill centralizer in FIG. 1. FIG. 3 shows, partly in section, a rear view substantially on line 3—3 in FIG. 2. FIG. 4 shows a fragmentary view corresponding to FIG. 3 but with the guiding arms in outwardly tilted or inactive position. FIG. 5 shows a section substantially on line 5—5 in FIG. 3. FIG. 6 shows a fragmentary front view of the drill centralizer in FIG. 2. FIG. 7, finally, shows a modified embodiment in a view corresponding to FIG. 4.

The drill centralizer shown in the figures consists of a base 10 which is provided with plane holed connecting surfaces 11 intended to be attached by means of bolts to the forward end of a feed bar, not shown. The feed bar supports in known manner a rock drilling machine slideable thereon as well as a drill steel and appurtenant feeding devices. The base 10 is provided with three bosses 12 into which are screwed long parallel bolts 13, which on one hand penetrate a front plate 15 and on the other traverse spacing tubes 16 lying between the front plate 15 and the bosses 12. By tightening the bolts 13 the front plate 15 and the spacing tubes 16 are connected to form a unity with the base 10. For securing the bolts 13 against being shaken loose, a locking plate 17 may be laid underneath the bolt heads and may be provided with upturned locking portions 18.

The two upper spacing tubes 16 form pivots for guiding arms 19 and 20 which project in upward direction from the base 10 and at their upper ends form semi-cylindrical guides 21 for the drill steel, not shown. In order that the guides 21 in active position shall provide a distinct centering position coaxially relative to the

2

axis of the drill steel the guiding arms 19, 20 are provided with slanting abutment faces 22, 23 adjacent the guides 21 which prevent relative gliding between the arms 19 and 20. The guiding arm 20 is provided with upwardly pointing ears 24 in which a pivot 25 is journaled. The pivot 25 forms part of a locking arm 26 swingably journaled between the ears 24. On the outer end of the locking arm 26 a washer 28 is fixed by means of a locking pin 27. Against the washer there is supported a helical spring 29 arranged around the locking arm which spring bears against the inside of a handle sleeve 30 slidably arranged on the locking arm. The handle sleeve 30 carries at its outer end a handle 31 while its inner end is tapered conically at 32. The locking arm 26 is intended for entering between upwardly turned ears 33 on the guiding arm 19 and the conically pointed portion 32 of the handle sleeve 30 coacts with conical recesses 34, FIG. 1, in the ears 33. By pulling the handle 31 and turning of the locking arm 26 on the journals of the pivot 25 the locking arm may be brought down between the ears 33 with the spring 29 compressed. If the handle is released in this position the conically pointed portion 32 of the handle sleeve 30 enters the recesses 34 and locks the guiding arms 19, 20 in active position.

The guiding arms 19, 20 are double-armed or bell crank levers carrying a pair of arms 35, 36 opposed to the guides 21 and pointing in the direction of each other. The arm 35 is provided with a pair of parallel bores 37 extending radially inward towards the spacing tube 16. In each of the bores 37 there is inserted a helical spring 38 under precompression between the spacing tube 16 and a substantially semi-cylindrical journal body 39 extending in parallel relation to the spacing tubes 16. The journal body 39 is provided with recesses 40 arranged coaxially with the bores 37 for receiving one end of the helical springs 38 and from the journal body 39 there projects a pair of spring guiding pins 41 into the springs 38 and the bores 37. The journal body 39 is pivotally journaled in a semi-cylindrical recess 42 formed in the end of the arm 36 of the guiding arm 20.

The front plate 15 is at its upper portion provided with a rearwardly directed portion 43 forming a downwardly turned plane abutment 44. The arm 36 on the guiding arm 20 is provided with an abutment 45 intended for cooperation with the abutment 44.

When the drill centralizer is to be placed from the active position illustrated in FIG. 3 into inactive position according to FIG. 4, the operator, standing for example at the side of the drill centralizer opposite to the handle 31, seizes the handle 31 and pushes the handle sleeve 30 forwardly in order to disengage its conically pointed portion 32 from the recesses 34 in the ears 33 on the arm 19. Thereupon the locking arm 26 is turned by the handle 31 on the journals of the pivot 25 about 180 degrees, whereupon the operator by pulling the handle farther away from the drill steel turns the guiding arm 20 around its spacing tube 16 in clockwise direction in FIG. 3. The turning movement is transmitted by the arm 36 and its cylindrical recess 24 to the journal body 39, which is urged to follow the arm 36 while compressing the springs 38. The spring guiding pins 41 of the journal body 39 during the course of this produce coupled swinging of the arm 35 and the guiding arm 19 around its spacing tube 16 counterclockwise in FIG. 3, whereby full synchronization of the movement of both guiding arms 20,

19 is effected. During swinging of the guiding arm 20 the arms 35, 36 pass the central horizontal plane through the axes of the spacing tubes 16 acting as pivots. In said position the springs 38 are compressed to a maximum degree and are in dead point or snap-over point position. Having passed the snap-over point position, the springs 38 will again expand and will produce through snap action displacement of the guiding arms into inactive position, FIG. 4, in which the abutment 45 of the arm 36 by the springs 38 is kept pressed against the abutment 44 of the front plate 15 whereby the guiding arms 19, 20 are firmly retained in inactive position.

Return of the guiding arms 19, 20, to active position is performed simply by pushing and displacing of the arm 20, FIG. 4, in the direction of the drill steel. After an initial compression the springs 38 again pass their snap-over point position, whereupon they under the expansion will cooperate towards bringing both guiding arms 19, 20 simultaneously into active position for retaining them therein. Finally the locking arm 26 is turned by means of the handle 31 down between the ears 33 in a manner to bring the handle sleeve 30 in engagement with the locking recesses 34, thereby positively interlocking the guiding arms 19, 20.

As an alternative the spring means 38, 39 in FIG. 4 may, as shown in FIG. 7, be exchanged for a massive, for example prismatic rubber block 46 inserted and fixed under axial precompression in corresponding aligned apertures 47 in the arms 35, 36 turned inwardly in the direction of each other. Operation of this arrangement is fully identical with operation of the embodiment in FIGS. 1-6.

The embodiments of the invention described above and shown in the drawing should only be considered as examples and the invention may be modified in many further ways within the scope of the claims following hereinafter.

What I claim is:

1. In drill steel centralizer apparatus of the character described for guiding the drill steel of a rock drilling machine and having a base for attachment to said machine and a pair of opposed guiding arms having pivotal connections to said base and being movable toward and away from each other from a guiding position adjacent each other to a non-guiding position away from each other, and a guiding surface disposed on each of said arms for mutual cooperation to form a guiding opening in said guiding position of said arms, the combination which comprises a second pair of arms rigidly disposed on said guiding arms and extending radially from said pivotal connections thereof on the ends thereof opposite said guiding surfaces, said second arms extending toward each other in opposed relationship, axially compressible resilient means disposed under compression between said second arms, pivot means on one of said second arms for connecting one end of said resilient means pivotally to said arm, means on the other of said second arms for connecting the other end of said resilient means slideably to said arm for guided axial movement of said resilient means with respect to said arm while being angularly rigid relative thereto, and means in said resilient means providing substantial lateral rigidity thereof whereby said resilient means has a snap-over point in an intermediate position of swing of said guiding arms, so that movement of one of said guiding arms past said snap-over point causes said resilient means to move the other said guiding arm for snapping said guiding arms into said guiding position at one side of said snap-over point and into said non-guiding position at the other side thereof and for holding said guiding arms in said selected positions thereof.

2. Drill steel centralizer apparatus as recited in claim 1 in which a pair of pivots are disposed on said base for connecting said guiding arms and in which said pivots are parallel to each other and to the axis of a drill steel to be guided.

3. Drill steel centralizer apparatus as recited in claim 1 in which said guiding arms and said second arms thereon are bell crank levers having a longer and a shorter arm extending from the pivotal connections thereon with the long arm forming the guiding arm thereof and the shorter arms disposed in opposed relationship to each other with said resilient means compressed and interposed between said short second arms.

4. In drill steel centralizer apparatus of the character described for guiding the drill steel of a rock drilling machine and having a base with a pair of bell crank levers pivotally disposed thereon, said bell crank levers having a long arm and a short arm with said pair of long arms movable from a guiding position adjacent each other to a non-guiding position away from each other and said short arms extending in opposed relationship to each other, the combination which comprises a guiding surface disposed on each of said long arms for cooperating with each other to form a guiding opening in the guiding position of said long arms, a spring between said short arms and connected thereto whereby movement of one lever brings about synchronized movement of the other lever by having a snap-over point in said spring in an intermediate position of swing of said levers for snapping said

20 long arms into guiding position at one side of said snap-over point and into non-guiding position at the other side thereof, and a rigid spring guide disposed in said spring for providing the connection between said short arms and for synchronizing the movement of said levers.

30 5. Drill steel centralizer apparatus as recited in claim 4 in which an abutment is disposed on said base for limiting the movement of said short arms in the non-guiding position thereof.

35 6. Drill steel centralizer apparatus of the character described having a base with a pair of guiding arms pivotally disposed thereon and cooperating guiding ends on said guiding arms, said guiding arms being bell crank levers and pivotable on said base from a guiding position with said guiding ends adjacent each other to a non-guiding

40 position with said guiding ends away from each other and with arms on said levers at the ends thereof opposite said guiding ends disposed in opposed relation to each other, the combination which comprises a resilient member in engagement with and disposed between said last mentioned arms, said resilient member having a snap-over position in an intermediate position of swing of said guiding arms for snapping said guiding arms into guiding position at one side of said snap-over point and into non-guiding position at the other side thereof and for retaining said guiding arms in the selected positions thereof.

50 7. Apparatus as recited in claim 6 in which said guiding arms are substantially equal in form and are pivotally mounted on said base in opposed relation to each other.

55 8. A drill steel centralizer apparatus of the character described for guiding a drill steel of a rock drill and having a base, a pair of guiding arms pivotally disposed on said base, opposed cooperating guiding ends on said guiding arms with said guiding arms being bell crank levers substantially equal in form and mounted in opposed relationship to swing on said base from a guiding position with said guiding ends thereof adjacent each other to a non-guiding position with said guiding ends away from each other and with the arms thereof opposite said guiding ends extending toward each other, the combination which comprises opposed sockets on said last

60 mentioned arms, a precompressed rubber body disposed between said sockets, said body having a snap-over position in an intermediate position of said swing of said levers for snapping said guiding arms into guiding position at one side of said snap-over point and into non-guiding position at the other side thereof and for retaining said guiding arms in the selected positions thereof, with said rubber body having sufficient rigidity to move 70 one of said arms past the intermediate position in re-

sponse to movement of the other said arm past its respective intermediate position.

9. Apparatus as recited in claim 8 in which cooperating locking means are disposed on said guiding arms of said bell crank levers for locking said guiding arms in 5 the guiding position thereof.
